UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

ELECTRICAL IGNITION SYSTEM FOR INTERNAL-COMBUSTION ENGINES.

1,139,121.

Specification of Letters Patent.

Patented May 11, 1915.

Application filed March 25, 1912. Serial No. 685,945.

To all whom it may concern:

Be it known that I, GOTTLÖB HONOLD, engineer, a subject of the German Emperor, residing at 11-13 Hoppenlaustrasse, Stuttgart, Germany, have invented certain new and useful Improvements in Electrical Ignition Systems for Internal-Combustion Engines; and I do hereby declare the following to be a full, clear, and exact description of the invention, such as will enable others skilled in the art to which it appertains to make and use the same.

The invention relates to electrical ignition systems for internal combustion engines, and particularly to systems of ignition, in which there is one current supply for service ignition during running, and a second current supply independent of the first for starting ignition.

It is generally recognized that service ignition during running of an internal combustion engine is performed better by an ignition machine driven from the engine than by a battery. A system having a single ignition machine is not, however, well suited to ignition during starting, because in those cases where the engine still retains in one or more of its cylinders a combustible mixture which has been partially compressed there as the engine came to rest it is not possible to take advantage of this situation and start the engine by ignition without cranking; and even in those cases where it is necessary to crank the engine to draw a combustible mixture into the cylinder such an ignition system requires that the engine should be cranked violently, until the ignition machine is turned at practically its normal running speed, to produce an ignition spark. On the other hand it is not feasible to provide an arrangement in which the single ignition machine can be turned independently of the engine shaft because the ignition machine must be positively connected in fixed and invariable relation to the engine shaft to assure timely service under all circumstances. A single battery ignition is not entirely satisfactory because the battery is not nearly so reliable as the ignition machine for service ignition, and because with a single battery it is necessary to extend the adjustment of the period of ignition over a comparatively large angle in order that the ignition may be sufficiently retarded during starting and

sufficiently advanced during running. These 55 considerations have led to the adoption of ignition systems in which a service ignition machine is directly connected to the engine for running ignition, and a battery is used for starting ignition. Such a system has, 60 however, the disadvantage that the battery ignition has to be cut out by hand as soon as the service ignition begins, and the character of the spark is limited by the condition and the output of the battery. 65

In accordance with the present invention a system of ignition is provided in which a service ignition machine is directly connected to the engine for running ignition, whereby all the advantages of this reliable type of 70 service ignition are conserved, and for starting ignition there is provided a separate ignition machine well designed to produce an effective starting spark, and being provided with independent driving means capable of rotating its shaft at a sufficient speed to produce such sparks. Such an ignition machine may be conveniently mounted upon the dash-board of a motor car within reach of the chauffeur, and will produce sparks only 75 so long as it is driven by its independent driving means. With such an arrangement, it is possible, if a charge of combustible mixture remains in one of the cylinders of the engine, to start the engine without cranking 80 by actuating the driving means of the starting ignition machine, and such actuation may be continued, and the speed of drive increased until there is produced a sufficient spark for ignition even under unfavorable 85 circumstances, and until the service ignition begins, whereupon the chauffeur will cease to operate the starting ignition machine and no further sparks will be produced thereby. 90

In order to provide in such a system, for 95 ignition in those cases where cranking is necessary, the present invention contemplates a disengageable coupling between the engine shaft and the starting ignition machine; and in the preferred form of the invention this arrangement takes the form of a disengageable coupling between the starting crank and the ignition machine, so that the starting ignition machine is disconnected from the shaft as soon as the crank is automatically thrown out by the turning of the shaft under its own power, and by reason of the disengageable coupling between the 100 105

crank and the ignition machine the actuation of the ignition machine independently of the crank is possible.

The invention may be embodied in a system in which there is one set of spark plugs for the service ignition machine and another set of spark plugs for the starting ignition machine, or it may be embodied in a system having a single set of plugs and a distributor common to the two ignition machines, such as that which constitutes the joint invention of this applicant and Messrs. Rall and Mumprecht and which is disclosed in United States Letters Patent No. 1,014,824, of Jan. 16th, 1912.

The preferred embodiment of the invention will be particularly described in connection with the accompanying drawings in which—

Figure 1 shows in elevation and Fig. 2 in plan, the application of the invention to a four-cylinder engine; Figs. 3 and 4, are diagrams of circuit connections; Fig. 5 is a perspective view showing the starting ignition machine on the dash-board of a motor car, together with the connection between the ignition machine and the crank; Fig. 6 is a front elevation of the motor car showing said connection; Fig. 7 is a detail of the connection; and Fig. 8 is an elevation partly in section of the casing of the starting ignition machine showing the disengageable coupling between the ignition machine and the crank, together with the independent driving means for the ignition machine.

In Figs. 1, 2, 3 and 4, *a* is the service ignition machine, which may be of any well known type, and is shown in this case as an ignition machine having a primary winding *b* and a secondary winding *d*. The interrupter *c* is operatively connected to the engine, while the brush *f* pressing on the slip ring *e* is electrically connected with an appropriate distributor contact. The source for starting ignition is the ignition machine *i* with primary winding *k*, secondary winding *m*, interrupter *l*, and slip ring *n*. The brush *o* for slip ring *n* is electrically connected with an appropriate distributor contact. In Fig. 3 is shown a distribution system like that of the above-mentioned U. S. patent in which the brush *f* is connected to the contact *g* of the distributor *h*, and the brush *o* is connected to distributor contact *p*. The segments *q₁*, *q₂*, *q₃*, and *q₄*, of the distributor *h* are electrically connected with respective spark plugs 1, 2, 3 and 4, of the cylinders as shown. In Fig. 4 the secondary winding *d* is connected to the contact *g'* of the distributor *h'* the segments of which are connected to one set of spark plugs 5, 6, 7 and 8, while the secondary winding *m* is connected to the contact *p'* of a distributor *h²*, the segments of which are connected to a separate set of plugs 9, 10, 11 and 12. If

now the engine has been brought to rest by cutting off the service ignition, the four pistons will be substantially in the position shown in Fig. 1, and cylinders 13 and 14 will contain partly compressed combustible mixture capable of starting the engine upon ignition. Under such circumstances, the engine may be started by rapidly rotating the shaft of the starting ignition machine *i* by means of the hand-crank *x* or any other suitable means. The current produced in the secondary winding *m* is conducted to the distributor contact and thence to the spark plug of the cylinder 13, so that a spark is generated and the partly compressed combustible mixture in that cylinder is ignited, whereupon its piston is driven downward as indicated by the arrow. In this way the engine is set in motion and as soon as the speed has increased so that the service ignition machine *a* is rotated at sufficiently high speed the service ignition current is produced and the engine continues to rotate. If the rotation of the engine produced by the starting ignition in cylinder 13 is not sufficiently rapid to produce service ignition then the actuation of the starting ignition machine *i* must be continued, generating starting sparks in those cylinders with which the starting ignition machine is successively connected, until the service ignition begins. Thereupon the actuation of the starting ignition machine is discontinued and it produces no further sparks.

It will be observed that the arrangement of the distributors is such that when the engine is at rest the service ignition machine is connected with that distributor segment which corresponds to the spark plug of that cylinder which is in the compression stroke, while the starting ignition machine is connected to that distributor segment which corresponds to the spark plug of that cylinder which is in the expansion or working stroke. If now it is desired to start the engine when there is no combustible mixture in any cylinder, it is necessary to provide a connection between the engine shaft and the starting ignition machine, and this is preferably effected by means of a disengageable connection between the crank and the starting ignition machine. To this end the crank *r*, which has the ordinary ratchet engagement with the engine shaft carries a sprocket wheel *r'* which through the chain *r²* drives a sprocket wheel *r³* on the end of a flexible shaft incased in a protecting cover *r⁴* and extending to the starting ignition machine within the casing *s* on the dash-board. The squared end *t* (see Fig. 8) of the flexible shaft enters a cup *t'* rotatably mounted in the wall of the casing *s* and constituting one member of a saw-tooth coupling of ordinary form. The outer member *t²* of this coupling is splined on the shaft

x' of the crank *x*, which is journaled at one end in the front wall of the casing *s* and at the other end in the central portion of the cup *t'*. The member *t²* is spring-pressed 5 into engagement with the member *t'* by the spring *u* surrounding the shaft *x'*. On the shaft *x'* is secured the pinion *w* which gears with a pinion (not shown) on the shaft of the ignition machine *i*. With this arrangement 10 it is possible to actuate the starting ignition machine from the driver's seat without turning the crank of the engine since in that case the inclined teeth of the saw-tooth clutch slip over one another and 15 permit the free rotation of the shaft *x'* to turn the shaft of the ignition machine *i* at high speed. On the other hand, if it is necessary to crank the engine the turning of the crank *r* rotates the flexible shaft by way 20 of the sprocket wheels *r'* and *r²* and the chain *r²* and the rotation of the flexible shaft is imparted to the shaft of the ignition machine through the clutch members *t'* and *t²*, the shaft *x'* and the pinion *w*.

25 Having thus described my invention, what I claim is:

1. In an ignition system for internal combustion engines, the combination with a service ignition machine having a positive 30 driving connection to the engine, of a hand-crank for starting the engine, a starting ignition machine, and mechanism for effecting a driving connection between the starting ignition machine and the engine shaft 35 during the cranking operation; substantially as described.

2. In an ignition system for internal com-

bustion engines, the combination with a service ignition machine having a positive driving connection to the engine, of a hand-crank for the engine having a ratchet engagement with the engine shaft, a starting ignition machine, and a driving connection between the crank and the starting ignition machine; substantially as described. 40

3. In an ignition system for internal combustion engines, the combination with a service ignition machine having a positive driving connection to the engine, of a hand-crank for starting the engine, a starting 50 ignition machine, mechanism for effecting a driving connection between the starting ignition machine and the engine shaft during the cranking operation, said mechanism including a disengageable coupling, and independent driving means for the starting ignition machine; substantially as described. 55

4. In an ignition system for internal combustion engines, the combination with a service ignition machine having a positive 60 driving connection to the engine, of a hand-crank for the engine having a ratchet engagement with the engine shaft, a starting ignition machine, a disengageable driving connection between the crank and the starting ignition machine, and independent driving means for the starting ignition machine; substantially as described. 65

In testimony whereof I have affixed my signature, in presence of two witnesses.

GOTTLÖB HONOLD.
